UNITED STATES PATENT OFFICE.

LOUIS BUPRECHT, OF MONTCLAIR, NEW JERSEY, AND ALFRED G. KOLLSTEDT, OF NEW YORK, N. Y.

GRINDING MACHINE.

Application filed February 10, 1927. Serial No. 167,109.

This invention relates to a machine for performing grinding or like comminuting operations, and adapted to the requirements of various industries, such as color grinding and numerous other purposes, particularly where uniformity in the size of the ground articles is a desideratum.

The invention relates particularly to the type of grinding machine in which the material to be ground is fed by means of a feed screw or worm to a rapidly rotated and enclosed grinder. The invention aims to improve the efficiency and convenience of such machines, and in particular to provide for presenting material to the grinder in a compacted mass. This not only prevents the escape of dust through the feed entrance, but also results in finer and more uniform grinding than could otherwise be obtained. A further object of the invention is to present the material uniformly along the length of the grinder. This conduces to uniform grinding, and also permits the use of grinders of any desired length. The means by which these and other objects of the invention are attained may best be understood from a detailed description of an illustrative swing hammer grinding machine embodying the invention which is shown in the accompanying drawing, in which:

Fig. 1 is a plan view of the machine with the cover of the main casing and the feed hopper removed;

Fig. 2 is a transverse sectional view taken on the line 2—2 of Fig. 1;

Fig. 3 is a longitudinal sectional view taken on the line 3—3 of Fig. 1;

Fig. 4 is a fragmentary transverse section on the line 4—4 of Fig. 1; and

Fig. 5 is a detail view.

The machine illustrated includes a main casing 10 within which is a rotary grinder 11, a feed conduit 12 extending from the main casing, feed screws 13^a, 13^b, 13^c in the feed conduit, and a feed hopper 14 opening into the top of the feed conduit at a substantial distance from the main casing.

The grinder 11 is of known form, and consists of a plurality of alternately turned hubs 15 to which are pivoted hammers or beaters 16. The hubs 15 are assembled on the middle part of a main shaft 17 which extends across the casing 10, and is provided with bearings 18 carried by the side walls 19 of the casing. While the main casing may be made rec-

tangular as shown, it encloses a cylindrical grinding chamber 20 provided by a cylindrically curved cover 21 enclosing the top of the grinder and a cylindrically curved screen 22 located within the casing and enclosing the lower half of the grinder.

For preventing the pulverized material or dust which is formed in the grinding chamber 20 from entering the bearings 18, disks 23^a, 23^b, are fixed on the main shaft 17 at opposite sides of the grinder 11 and close to the inner surface of the side walls of the casing. Although these disks are shown as flat, they may be flanged or curved or otherwise deformed if desired, and for this reason the word "disk" as used herein is not to be understood to be limited to a flat disk. The disks 23^a, 23^b contain central openings which fit tightly on the shaft, so that no dust can pass between them and the shaft. The rapid rotation of the shaft, which is necessary for effective operation of the grinder, causes these disks to throw radially outward any dust or grit which may move along the shaft or along the central part of the casing towards the bearings 18. Such dust is thus prevented from entering the bearings. Furthermore, although the disks are not in actual contact with the side walls of the casing, they are located so near these side walls that any dust or grit which attempts to enter between them and the casing is immediately thrown out radially. Consequently no dust or grit can enter the bearings 18. This is an advantage of great practical importance, since when previous grinding machines of the same general character have been applied to grinding gritty materials, it has been found necessary to replace the shaft bearings at frequent intervals.

A feature of the invention consists in providing means for facilitating the removal and replacement of the screen 22. This is important since the mesh of this screen should correspond to the fineness of the grinding required. The side edges of this screen, which may be of the usual form of a thin screen plate mounted on a skeleton back plate or of other suitable form, are held in channels 24 provided in the inner surfaces of the side walls 19 of the main casing, as by ribs 25 cast or otherwise formed thereon. The upper or end edges of the screen are engaged and held by removable hold-down blocks 26, 27. The ends of the block 26 have a slidable engage-

ment with vertical grooves 28 formed in the side walls of the casing. This block is normally held down against one end edge of the screen by the cover 21, but may be lifted 5 out vertically to permit removal of the screen when this cover is removed. The block 27 contains a central opening which forms the inner end of the feed conduit 12 in which the screws 13^a, 13^b, 13^c are located, so that 10 this block cannot be raised vertically like the block 26. The grooves 28 in the side walls 19 in which the ends of this block are held are, therefore, made wider than the block, so that the block may be moved horizontally inward 15 to uncover the upper end of the screen 22, and thus to permit the application of a pressing instrument to this edge of the screen to force the screen out at the opposite end of the casing. If rigidly supported hammers 20 are used, this will, of course, be done when the grinder is so turned that none of the hammers are directly opposite the block 27. To retain the block 27 in its normal operative 25 position and out of the path of the beaters during the operation of the machine, filler pieces 29 are inserted in the grooves 28. These pieces are held in position by the cover 21. It is apparent that the arrangement described provides for ready removal and 30 placement of the screen, and at the same time holds the screen rigidly in its proper position during the operation of the machine. In order to prevent any possible protrusion of any part of the end edges of the screen into 35 the path of the ends of the hammers, or direct wearing contact of the rapidly moving material in the chamber with the end edges of the screen, the blocks 26 and 27 are provided at their lower inner edges with downwardly projecting flanges 26^a and 27^a, most 40 desirably tapered as shown, which when the parts are positioned extend in front of the screen edges.

Important features of the invention are embodied in the means for feeding the material to be ground into the grinding chamber 20. The feed opening 30 into this chamber from the conduit 12 is provided by the opening in the hold-down block 27. It is narrow but of 45 sufficient length to extend a substantial distance along the axial length of the grinder 50. When the feed conduit is arranged to feed the material in a horizontal direction as shown, the feed opening 30 is located substantially on the level with the axis of the grinder, although it is desirable to place the middle of the opening slightly above this axis so that the lower edge of the opening is 55 on the level with the axis.

The feed conduit 12 extends to the feed opening 30 and is most desirably of the same width and height as the feed opening. In order that the feed screws 13^a, 13^b and 13^c may 60 deliver the material to the grinder in a compacted mass, the feed conduit extends in such

a direction that the force of gravity on the material contained in it does not urge the material into the main casing, that is to say, the feed conduit has no, or substantially no downward inclination. For most materials, it most 70 desirably extends horizontally, as shown. The inner portion of the conduit is closed, while the top of the outer portion of the conduit is in communication through a supply opening 31 with the feed hopper 14. The 75 floor of the conduit 12 is formed to provide a plurality of semi-circular grooves 32^a, 32^b, 32^c extending lengthwise of the conduit. A plurality of feed screws 13^a, 13^b, 13^c, corresponding in number to that of these grooves, 80 are located in the feed conduit coaxially with the grooves, and in such manner that their threads just clear the grooves. The upper wall 33 of the enclosed inner portion of the conduit is formed to provide corresponding semi-cylindrical grooves 34^a, 34^b, 34^c which closely enclose the upper portions of the 85 threads of the screws.

The feed screws are supported entirely 90 from their rear ends. Each screw extends from a shaft 35 which is provided with spaced 95 bearings 36 located beyond the outer end of the feed conduit. Each screw is most desirably made integral with its supporting shaft. This mounting of the feed screws not only avoids the use of a bearing in the feed conduit, which would tend to obstruct the movement of the material, but also has the advantage of making it possible to extend the feed screws to a point very close to the periphery of the grinder. This results in finer and more efficient grinding than would otherwise be obtainable.

In order to supply the material uniformly 100 across the length of the grinder, all the feed screws are most desirably rotated at the same speed by a common driving means which, in the form shown, consists of a worm 38 engaging gears 39 of uniform size fixed on the 105 shafts of the screws. In order to provide for a constant ratio between the speed of the grinder and that of the feed screws during an operation of the machine, the worm 38 is connected with the main shaft 17, for example, by means of a belt 40 and appropriate belt 110 pulleys, as shown.

In the operation of the machine which has 115 been described, the material to be ground is placed in the hopper 14 in such manner that it falls by gravity uniformly across the feed conduit 12 through the opening 31. The material is fed forward toward the grinder in a uniform manner by the feed screws. The movement of the material through this conduit is caused only by the action of the screws which accordingly compact the material in the closed portion of the conduit as they force it forward. The screws deliver a compact 125 mass of material directly to the hammers of the grinder, which, moving upward past the 130

feed opening, successively strike the end of the compacted mass of material from below as it is forced into the grinding chamber, and act to comminute it. As the material becomes sufficiently comminuted, it passes through the screen 22, and may be collected in a bag 41 or other suitable receptacle at the bottom of the main casing 10. As will be understood by those skilled in the art, the fineness of the grinding may be regulated by changing the screen and by changing the speed of the grinder and the feed screws, and to some extent by changing the ratio between these speeds. The higher the speed of the grinder and the finer the screen, the finer the grinding. While the speeds at which the high speed grinder and the relatively low speed feed screws should be driven depend on the nature of the material being ground and the fineness of grinding required, it may be noted by way of illustration that the speed of the grinder has been varied from 500 to 5500 R. P. M., and that of the feed screws from 50 to 200 R. P. M., depending, as stated, on the fineness of grinding required, the kind of material being ground, and also on the size of the grinder and the size and pitch of the feed screws.

What is claimed is:

1. A machine of the class described, comprising a main casing, a feed conduit extending to an opening in the periphery of the main casing at an angle such that gravity does not urge the material in the conduit toward the main casing and provided with a supply opening at a substantial distance from its inner end, a feed screw in said conduit adapted to move material along the conduit and to force it into the main casing in a compacted mass, a plurality of beaters in the main casing, and means for moving said beaters so that they successively strike from below the compacted mass forced into the casing by the feed screw.

2. A machine of the class described, comprising a horizontal cylindrical main casing, a feed conduit extending horizontally to an opening in the periphery of the main casing and provided with a supply opening at a substantial distance from its inner end, a horizontal feed screw in said feed conduit adapted to feed material supplied through said opening into the main casing, a grinder in the main casing, beaters on said grinder, and means for rotating the grinder so that the beaters move upwardly across the inner end of the feed screw.

3. A machine of the class described, comprising a rotary grinder, a main casing enclosing a cylindrical chamber having a peripheral admission slot extending parallel to the axis of the grinder and substantially from one end of the grinder to the other, a feed conduit whose cross section corresponds to said opening extending to said opening and

provided with a supply opening in its top located a substantial distance from its inner end, and means in the feed conduit for compacting the material to be ground and forcing it through said slot at a uniform rate along the length of the slot.

4. A machine of the class described, comprising a main casing enclosing a cylindrical chamber having an oblong peripheral opening extending parallel to its axis and substantially from one of its ends to the other, a rotary grinder in the casing, a feed conduit whose cross-section corresponds to said opening extending to said opening and provided with a supply opening in its top located a substantial distance from its inner end, a plurality of feed screws located side by side in the feed conduit, and means for rotating all of said feed screws at the same rate.

5. A machine of the class described, comprising a main casing, a rotary grinder therein, a feed conduit extending to an opening in the periphery of the casing and having a supply opening at a substantial distance from its inner end, a shaft at the outer end of said conduit, spaced bearings for said shaft located beyond said opening, and a feed screw located in the conduit with its inner end close to the periphery of the grinder and wholly supported by said shaft.

6. In a machine of the class described, the combination of a wide, shallow, horizontal feed conduit having a plurality of longitudinal, semi-cylindrical grooves in its bottom, a plurality of feed screws in said conduit each of which is coaxial with one of said semi-cylindrical grooves, and driving means for said feed screws positively connected to each of them.

7. In a machine of the class described, the combination with a main casing, a rotary grinder therein, a feed conduit opening to the main casing, and a feed screw in the conduit with its inner end close to the periphery of the grinder and substantially on the level with its axis, of a screen support below the grinder, a cylindrically curved screen supported thereby, a removable block engaging the upper edge of the screen at the side of the grinder opposite to the feed screw, and a removable block which engages the other upper edge of the screen, contains an opening for the passage of the feed screw, and is mounted so as to slide longitudinally of the feed screw to expose said upper edge of the screen.

8. A pulverizing machine, comprising means for horizontally compacting material to be pulverized, and moving it horizontally, and beaters successively striking the forward portion of the compacted mass from below.

In testimony whereof, we have hereunto set our hands.

LOUIS RUPRECHT
ALFRED G. KOLLSTEDE.
